EYEGLASS CONSTRUCTION

George E. Nerney, Attleboro, Mass., assignor to
 Bay State Optical Company, Attleboro, Mass.,
 a corporation of Maine

Application January 5, 1943, Serial No. 471,379

3 Claims. (Cl. 88—47)

This invention relates to eyeglass construction and more particularly to the lens connecting portions thereof.

One of the objects of this construction is to provide a new and improved eyeglass construction. Another object is to provide a construction of the above character which is simple, practical, and thoroughly durable in use. Another object is to provide a construction of the above character which is neat and attractive in appearance and, at the same time, adapted to absorb the strains of extended usage. Another object is to provide a construction of the above character the assembly of which may be easily and quickly accomplished. Another object is to provide a construction of the above character which will be especially strong in certain vulnerable spots of common eyeglass construction. Still another object is to provide a construction of the above character wherein the individual parts, as well as their particular construction, are so designed as to reduce expenditure of materials or the like. A further object is to provide a construction of the above character in which there is a snug fit between the lenses and the parts connected thereto. Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which is shown one of the various possible embodiments of this invention,

Figure 1 is a front elevation of a lens having my endpiece and bridge connections mounted thereon;

Figure 2 is a fragmentary perspective view, on an enlarged scale, of the endpiece connection shown in Figure 1;

Figure 3 is a horizontal sectional view, on an enlarged scale, taken on the line 3—3 of Figure 1 prior to the assembly of the lens and the frame;

Figure 4 is a horizontal sectional view, on an enlarged scale, taken on the line 3—3 of Figure 1 after the assembly of the lens and the frame; and,

Figure 5 is an exploded perspective view, on an enlarged scale, of the endpiece connections shown in Figure 1.

Similar reference characters refer to similar parts throughout the several views of the drawing.

As conducive to a clearer understanding of certain features of this invention, it might here be

pointed out that certain difficulties are encountered in making a secure and durable connection between the mountings and lenses in frames of the fragile rimless type. Frames of this type are characterized by having lens connecting means on the ends of the temples and at the opposite ends of the bridge, and the retailer fits these mountings to the lenses prescribed for the customer. Very often these lenses are toric in shape, and to fit many of the present type of saddles to such lenses, considerable bending of the saddle by the retailer is required. Because of the smallness of the parts, a perfect fit between the lens and the saddle is seldom achieved, and it is well known that many fractures of lenses in rimless frames are caused when strains are placed upon imperfectly mounted saddles. These fractures may be caused by the loosening of the saddles which permits the lens screw to exert a "jacking" action on the lens hole as it is twisted sideways therein, or the saddle may exert undue strain against certain points on the lens faces due to the fact that the straps do not properly fit the lens faces. In the latter case, strains upon the saddle are transmitted to the lens at single points rather than being spread evenly over the portion of the lens face covered by the saddle, which results in the lens fracture. Accordingly, it is another object of this invention to overcome the above-mentioned difficulties, as well as many others.

It might here be noted that reference herein-after to an "outward" direction signifies a direction to the left or right of the bridge of an eyeglass frame in the direction of the temples, while the term "inward" denotes a direction opposite thereto. A "rearward" direction refers to a direction toward the face of the wearer, whereas the term "forward" denotes the opposite direction. An "upward" direction refers to a direction upwardly from the face of the wearer, while a "downward" direction is opposite thereto.

Referring now to Figure 1, a portion of a pair of rimless spectacles is shown which includes a bridge generally indicated at 10, a lens 11, an endpiece generally indicated at 12, and a pair of saddles generally indicated at 13 and 14. As saddles 13 and 14 and the parts of the mountings to which they are connected are substantially similar in construction, the description will be limited to saddle 14 and its connection to endpiece 12.

As best shown in Figures 2, 3, and 5, saddle 14, which is preferably made from thin resilient sheet metal, includes a leaf spring section 15 and a pair of ears generally indicated at 16 and 17. Leaf

spring section 15 extends upwardly and downwardly along, and abuts against, the lens edge 18. Ears 16 and 17, which are integrally connected to leaf spring section 15, extend inwardly over opposite faces of lens 11 (Figures 3 and 4), and their inner end portions 16a and 17a are preferably enlarged (Figure 5) and cup-shaped. Enlarged end portion 17a has a hole 19 extending therethrough, the diameter of which is preferably slightly larger than the diameter of lens screw 20, and enlarged portion 16a of ear 16 has an oval-shaped hole 21 therein, the length and width of which are, respectively, substantially and slightly greater than the diameter of the shank of lens screw 20.

Endpiece 12 (Figures 3 and 4), which is pivotally connected to temple 22 by screw 23, includes an arm portion 24 which extends inwardly substantially parallel to the face of lens 11 adjacent ear 17. Arm 24 is of substantially the same length as ear 17, and its enlarged inner end, which (Figure 5) is positioned adjacent the enlarged portion 17a of ear 17 when the saddle and arm are in assembled relationship, has a threaded hole 30 extending therethrough. This hole, which carries threads complementary to the threaded portion of lens screw 20, is in alignment with hole 19 extending through ear 17. The arm 24 is connected to ear 17 by a pin 25. This pin is connected to the rear face of ear 17 (Figure 5) in any suitable manner, such as by soldering, and extends through a hole 26 in arm 24. This pin 25 is secured to arm 24 in any suitable manner, such as by having its end headed over in a countersunk portion at the rear end of hole 26 (Figures 3 and 4).

As best shown in Figure 3 in which the assembled endpiece and saddle mounting are shown, prior to the connection of the lens thereto, pin 25 is positioned adjacent the outer end of ear 17 near its point of connection to leaf spring section 15. This permits the enlarged portion 17a of ear 17, which is cup-shaped, freedom of movement with respect to the arm 24 and lens 11 when the lens is being mounted on the saddle. Thus, referring to Figure 4, because of this freedom of movement, ear 17 acts as an independent cushioning means between arm 24 and lens 11 when screw 20 is in a set position, ear 17 having adjusted itself to the curvature of lens 11 to form a snug fit therewith as the screw is set.

Oval-shaped hole 21 in ear 16 coacts with lens screw 20 as the lens screw is set to insure a snug fit between the lens and this ear. Referring to Figure 3, ear 16 is curved forwardly from the lens face, and thus, as screw 20 draws this ear toward the lens face, the oval-shaped hole 21 in ear 16 permits the outer portion of ear 16 to move inwardly with respect to the lens face until the ear 16 has adjusted itself to fit the curvature of the lens face. Because of the shape of hole 21, this movement of ear 16 is permitted, as the edge of the hole in the ear does not strike against screw 20. When the screw is set, the ears exert a resilient force against the head of screw 20 which is of material aid in preventing the screw from loosening.

Thus, because of the manner of attachment of saddle 14 to arm 24, both resilient ears of the saddle are free to adjust themselves to the curvature of the lens faces as the lens screw 20 is set, thus insuring a snug fit between the saddle and the lens. Furthermore, the leaf spring section of the saddle is so positioned that it may be easily

adjusted to correctly fit the edge of the lens which is being mounted on the saddle.

Referring to Figure 1, the bridge 10 and its related parts, such as nosepad 36, which may be of any desired construction, providing that no portion of the bridge blocks or interferes with the free movement and adjustability of the leaf spring section of saddle 13, include an arm (not shown) extending over the rear face of the lens similar to the arm 24 of endpiece 12 and connected to the rear ear of saddle 13 by a connection similar to the connection between ear 17 and arm 24. Thus, the mounting disclosed is suitable for use in connecting either the bridge or endpieces of a rimless frame to the lenses. Furthermore, when the mounting has been secured to the lenses, a snug fit is obtained between the lens and the ears of the saddle, and the leaf spring section of the saddle resiliently resists movement of the lens upwardly and downwardly out of the position in which it normally lies.

It will thus be seen that I have provided a thoroughly practical and efficient construction in which the several objects mentioned hereinabove, as well as many others, are successfully accomplished.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

I claim:

1. In eyeglass construction, in combination, an endpiece including an arm member, said arm member having a threaded hole formed therein adjacent its inner end, a saddle member, said saddle member including a leaf spring section and a pair of ears integrally formed thereon, said ears being formed of thin resilient sheet metal and having their inner ends cup-shaped, means securing one of said ears to said arm member at a single point adjacent the point of connection of said last-mentioned ear to said leaf spring section and remote from the inner end of said ear whereby the inner portion of said last-mentioned ear is free to move with respect to said arm member during setting of the lens screw, said ears having holes extending through their cup-shaped portions, and a lens screw, said lens screw being adapted to pass through said holes and being threaded into the hole in said arm member, said point of connection between said ear and said arm being the only point of connection between said saddle member and said endpiece.

2. In eyeglass construction, in combination, a lens having a lens hole, an endpiece, said endpiece including an arm portion curving inwardly over the rear face of said lens, a saddle member, said saddle member including a leaf spring section adapted to contact the edge of said lens and a pair of resilient ears formed integrally thereon, one of said ears being positioned between the arm portion of said endpiece and said lens, means connecting said last-mentioned ear to said arm portion adjacent the point of connection of said last-mentioned ear to said leaf spring section and remote from the inner end of said ear whereby the inner portion of said last-mentioned ear is free to move with respect to said arm portion, the inner portions of said arm portion and ears having holes extending therethrough, and a lens screw adapted to pass through said ear and lens

holes and thread into the hole in said arm portion, said point of connection between said ear and said arm portion being the only point of connection between said saddle member and said endpiece, whereby, when said screw is set, said ears are free to conform to the curvature of the lens faces.

3. In eyeglass construction, in combination, a lens having a lens hole therein, an endpiece including an arm member extending over one face of said lens and having a threaded hole formed therein adjacent its inner end, a saddle member including a leaf spring section and a pair of resilient ears, one of said ears being positioned between said arm member and said lens, means

15 connecting said last-mentioned ear to said arm member at a single point adjacent the point of connection of said ear to said leaf spring section and remote from the inner end of this ear, said 5 point of connection between said ear and said arm member being the only point of connection between said saddle member and said endpiece, and lens screw means extending through holes in the inner portions of said ears and said lens hole and threaded into the hole in said arm member, 10 whereby the inner portion of the ear connected to said arm member is free to move with respect to said arm member during the setting of the lens screw.

GEORGE E. NERNEY.
